DESIGN FOR A CEILING REEL HOUSING

Alexander P. Fox, University City, Mo., assignor
to Lincoln Engineering Company, St. Louis,
Mo., a corporation of Missouri

Application August 22, 1947, Serial No. 141,001

Term of patent 3½ years

(Cl. D52—2)

To all whom it may concern:

Be it known that I, Alexander P. Fox, a citizen
of the United States and a resident of University
City, St. Louis County, Missouri, have invented
a new, original, and ornamental Design for Ceiling
Reel Housing, of which the following is a speci-
fication, reference being had to the accompanying
drawing, forming part hereof, in which

Fig. 1 is a front elevation of a ceiling reel hous-
ing, showing my new design;

Fig. 2 is a side elevation; and,

Fig. 3 is a perspective view.

I claim:

The ornamental design for a ceiling reel hous-
ing, substantially as shown.

ALEXANDER P. FOX.
